UNITED STATES PATENT OFFICE

130,114

DESIGN FOR A MAH-JONGG COIN INDICATOR OR SIMILAR ARTICLE

Grace Bloom, New York, N. Y.

Application May 15, 1941, Serial No. 100,944

Term of patent 3½ years

To all whom it may concern:

Be it known that I, Grace Bloom, a citizen of the United States of America, residing at 253 West 72nd Street, New York city, county and State of New York, have invented a new, original, and ornamental Design for a Mah-Jongg Coin Indicator or Similar Article, of which the following is a specification, reference being had to the accompanying drawing, forming a part thereof.

Fig. 1 is a plan view of a mah-jongg coin indicator showing my new design.

Fig. 2 is an edge view thereof.

I claim:

The ornamental design for a mah-jongg coin indicator or similar article, as shown.

GRACE BLOOM.
